SHOE

Nathan Swartz, Lynn, Mass.

Application November 25, 1938, Serial No. 242,247

1 Claim. (Cl. 36—57)

This invention relates to the manufacture of shoes, particularly women's shoes, such as pumps, slippers and the like.

In the manufacture of women's shoes of the aforesaid type considerable difficulty has been encountered in providing the requisite degree of flexibility at the instep portion to insure wearing comfort, without sacrificing the snug-fit and neat appearance desired in shoes of this type. Although numerous attempts have been made to overcome this difficulty, such attempts usually involve the employment of expandible inserts, tongues and the like elements which not only tend to produce a bulky appearance, but also to increase the cost of manufacture.

The principal objects of the present invention are to overcome the aforementioned difficulty and to provide an improved shoe and a simple and efficient method of making the same, whereby the desired degree of flexibility at the instep portion may be obtained without sacrificing appearance or increasing the cost of manufacture.

Further objects will be apparent from a consideration of the following description and accompanying drawing, wherein:

Fig. 1 is a plan view of an assembled upper made in accordance with the present invention;

Fig. 2 is an enlarged section on the line 2—2 of Fig. 1;

Fig. 3 is an enlarged section on the line 3—3 of Fig. 1;

Fig. 4 is a perspective view of a shoe embodying the present invention; and

Fig. 5 is an enlarged section on the line 5—5 of Fig. 4.

In accordance with what is now considered to be the preferred procedure, a cut-out shoe upper, including the upper, lining and a length of elastic piping may be assembled in the usual manner, and the top marginal portion or edge of the upper is first secured to the elastic piping by a line of stitching which extends from the rear of one of the quarter portions forwardly about the throat or instep, and thence to the rear end of the other quarter portion. Subsequently, a second line of stitching is applied which extends through the upper, elastic piping and the lining, this second line of stitching being either superposed on or applied in closely spaced relation to the first line of stitching at the rear portion of the upper and being spaced appreciably from the first line of stitching at the throat portion of the upper. The assembled upper may then be lasted in the usual manner, and either before or after lasting the edge of the lining extending upwardly

beyond the second line of stitching may be trimmed down so as to be substantially concealed when the shoe is worn.

I have found that in a shoe constructed as above set forth, the spaced lines of stitching at the instep portion define a zone of increased flexibility which not only permits the instep portion to conform snugly with the contour of the foot, but also allows a certain amount of "give" or pliability which insures wearing comfort.

Referring to the drawing, the numeral 1 designates an upper including an outer member 2 which may be of patent leather or any other suitable material, a lining 3, and an elastic piping 4 having a beaded upper edge and a body portion 10 interposed between the top edges of the upper and lining. The piping 4 is preferably pimpled or notched at the throat portion of the upper so as to avoid bulging, and it may then be secured to the upper 2 by a line of stitching 5 which extends entirely about the marginal portions of the upper. The lining 3 is secured to the upper 2 and piping 4 by a second line of stitching 6 which is in closely spaced relation to the first line of stitching 5 at the rear portion of the upper, but 15 is spaced appreciably, that is, of the order of one-eighth of an inch or more, from the first line of stitching at the throat portion of the upper, thereby to define a zone 8 of increased flexibility and extensibility, as shown in Figs. 1, 20 30 and 5.

Either before or after lasting the assembled parts of the upper any excess lining extending outwardly beyond the stitching 6 may be skived or trimmed off, as shown in Figs. 3 and 5. The 35 lasting operations may be performed in the usual manner and the shoe completed in accordance with conventional shoemaking practices.

In a shoe made in accordance with the present invention, the rear portions of the top edges of the upper are relatively firm and are directed slightly inwardly so as to insure a snug fit. The front or instep portions of the shoe possess an appreciable flexibility, relative to the rear portion, particularly at and about the center of the 40 instep or throat of the upper, and due to the spaced lines of stitching the zone 8 possesses sufficient outward "give" or yieldability to eliminate the biting effect which is usually encountered in 45 shoes made in accordance with conventional practices. Moreover, because of the flexibility and outward yieldability of the zone 8, the instep portion of the upper more readily conforms to the contour of the foot of the wearer, and hence 50 55

not only insures wearing comfort but also a snug, attractive fit.

Furthermore, it will be noted that in a shoe made in accordance with the present invention, the desired flexibility at the instep portion is attained without the necessity of using expandable inserts and the like expedients which appreciably increase the cost of manufacture, and by avoiding the use of expandable inserts and the like, the attractive appearance of pumps and similar types of shoes is not in any way sacrificed or impaired.

While I have shown and described one desirable embodiment of the invention, it is to be understood that this disclosure is for the purpose of illustration, and that various changes in shape, proportion and arrangement of parts may be made without departing from the spirit and scope of the invention as set forth in the appended claim.

20 I claim:

A shoe of the class described, including an upper, a lining and an elastic piping interposed between the upper and lining, the piping having a beaded edge which projects outwardly beyond the upper edges of the upper and lining, the upper and piping being secured together by a line of stitching extending around the top marginal portions of the upper, the lining being secured to the upper and piping by a second line of stitching disposed in closely spaced relation to the first 10 line of stitching at the rear portion of the upper, but spaced at least approximately $\frac{1}{8}$ inch from said first line of stitching at the throat portion of the upper, the portion of the lining at and adjacent to the throat of the upper lying between 15 the first and second lines of stitching being trimmed off, thereby defining a zone of increased flexibility and extensibility at and adjacent to the throat portion.

NATHAN SWARTZ. 20
